UNIDECWOOD COMPUTING MACHINE COMPANY, OF NEW YORK, N. Y., A CORPORATION
OF NEW YORK.

COMPUTING MACHINE.

1,203,919.

Specification of Letters Patent. Patented Dec. 19, 1916.

Application filed July 26, 1912. Serial No. 2,002,662.

To all whom it may concern:

Be it known that I, Charles H. Conrad, a citizen of the United States, residing in New York city, in the county of New York and State of New York, have invented certain new and useful Improvements in Computing-Machines, of which the following is a specification.

This invention relates to a hand adding machine.

It is the purpose of this invention to provide a neat compact adding machine which will be easy to operate, simple in construction, strong, durable, and yet light enough to be easily carried about in the hand or pocket from one place to another, as from one set of books to another set of books.

In carrying out this invention certain features found in the Hanson type of adding machine, described in Patent No. 905,421, dated December 1, 1908, have been used in connection with the improvement.

A series of rack bars are provided one for each digit column or decimal place desired. These rack bars each carry a set of nine pins, which are capable of being individually offset with respect to their fellows to determine the extent of subsequent movement of the rack bars by a general operator. Each pin has a corresponding key by means of which it is set. The keys may be spread out so that they may be conveniently operated, and their stems converged toward the more closely set nest of pins. The rack bars have a straight sliding movement without vertical movement and run in grooves formed between guiding blocks so that the rack bars will be maintained with the rack portions thereof in proper mesh with their respective gears carried by dial or computing wheels.

The dial wheels exhibit the numbers run up thereon through a sight aperture in the casing. Special means is provided for tens-carrying and also for preventing an incomplete movement of the general operator.

Other features and advantages will hereinafter appear.

In the accompanying drawings, Figure 1 is a vertical section taken from front to rear. Fig. 2 is a horizontal plan view with the cover plate removed and partly in section to show the underlying structure. Fig. 3 is an enlarged fragmentary view in elevation, partly in section showing the pin restoring mechanism. Fig. 4 is an enlarged frag-

mentary view showing a detail of the lock for forcing a complete stroke of the general operator before movement in the opposite direction. Fig. 5 is a vertical transverse section. Fig. 6 is a detail view of one of the computing wheels. Fig. 7 is a view of the parts shown in Fig. 6, taken in vertical section at right angles to the view in Fig. 6. Fig. 8 is a detail of the tens-carrying mechanism for one computing wheel, showing the same in its silent or ineffective position. Fig. 9 is a view similar to Fig. 8, showing the assisting segments in the act of rotating the tens wheel. Fig. 10 is an enlarged sectional view, showing the detail of the tens carrying mechanism. Fig. 11 is a fragmentary view in elevation, showing the mechanism for returning all of the dial or computing wheels to zero. Fig. 12 is a perspective view of the shaft which returns all the computing wheels to zero.

Referring more particularly to the separate parts of this device as embodied in the form shown in the drawings, 1 indicates the numerical keys of which there is a series from "1" to "9" for each digit or decimal column desired; thus the machine is of the "81 key" type. These keys 1 are spread apart from each other a sufficient distance to enable them to be operated conveniently. The keys 1 have straight downwardly-projecting stems 2 which are guided by openings in the casing 3 at their upper ends. Said stems extend straight down through openings in a plate 4 within the casing, and then the stems converge so that each cooperates with its respective pin 5 in a nest of pins 5 which are more closely and compactly arranged than the keys 1. Springs 6 bearing against the plate 4 return the keys 1, after having been depressed, to their normal raised positions.

The pins 5 are supported in aligned groups of nine, corresponding to the numbers "1" to "9" on bars 7, which bars are provided at their rear ends with racks 8 and hence may be called rack bars. As will be seen by reference to Fig. 3, the pins 5 are mounted in vertical openings in the rack bars 7 and are normally held in a raised position by means of spring-pressed ball detents 9 which engage annular grooves 10 in the pins 5.

The rack bars 7 are held in a raised position from the bottom of the casing 3 so that the pins 5 can be set to project downwardly,

2
by means of legs 10 and 11, the latter of which are arranged to travel in guiding ways or slots 12 provided between guiding blocks 13. This arrangement enables the 5 racks 6 of the bars 5 to always mesh with gears 15 of computing or dial wheels 16. These computing or dial wheels 16 have numbers thereon arranged from "0" to "9," and are adapted to exhibit these numbers 10 through a sight opening 17 provided in the top or cover of the casing 9.

The connection of the gears 15 in each instance to the number-bearing portion of the computing or dial wheel is such that a 15 forward movement of the associated rack bar 5 will rotate the computing wheel, but a rearward motion will rotate the gears 15 idly without affecting the relative position of the dial wheels with respect to the sight 20 opening 17. This arrangement will be seen by reference to Figs. 6 and 7, to include a ratchet wheel 18 of which there is one for each of the gears 15. The ratchet wheel 18 has teeth inclined in one direction so that 25 they will engage and be connected rigidly to a spring-pressed dog 19 during the rotation of the gear 15 in one direction, and so that they will automatically slide by the dog 19 during the rotation of the gear 15 for a 30 return movement of the racks 5.

The dog 19 is slidingly mounted on the number-bearing portion of the computing or dial wheel so that this mechanism forms a one-way ratchet connection between the 35 gear 15 and the body portion of the dial or computing wheel. It will be seen by reference to Fig. 7 that the gear 15 and the ratchet wheel 18 are loosely mounted on a hub 20 of the computing or dial wheel so as 40 to be capable of rotating relatively thereto.

For the purpose of carrying tens from one computing wheel to the computing wheel of next higher denomination, each computing wheel is provided with a single tooth 21 45 which is adapted to engage a mutilated gear 22 when the accordant dial wheel shifts from "9" to "0," so that this gear is shifted through a ninth of a revolution. The mutilated gear 22 has every third tooth cut away 50 so that it presents when inactive, blank portions thereof to a corresponding assisting segment 23 mounted on shaft 24. There is one of these assisting segments 23 for each of the computing wheels, with the exception 55 of the one of highest denomination, and they are arranged spirally on the shaft 24 so as to come successively into action from lowest denomination to highest, whereby tens are carried from a lower computing wheel to a 60 higher computing wheel, and a tens completed by the tens-carrying operation will be carried to the next higher computing wheel.

The assisting segment 23 rotates the mutilated gear 22 through two-ninths of a revolution so that a three-toothed wheel 25, which

is secured to the mutilated gear 22, will be rotated in all a third of a revolution, whereby one of the teeth 25^a will engage a gear 26 fast on the next higher computing wheel 16 to rotate this computing wheel one-tenth 70 of a revolution.

The mutilated teeth of the gear 22 while cut away enough to avoid the assisting segments 23, are of sufficient magnitude to enable spring-pressed detents 27 to hold them 75 in any adjusted position. The computing wheels 26 are also engaged by spring-pressed detents 28, whereby the computing wheels will be yieldingly held in their proper positions so that overthrow of the computing 80 wheels is prevented.

The rack bars 5 receive their motion from a general operator 29 which is shown to comprise a pair of side bars 30 spaced apart from each other and connected by a transverse bar 31 and a transversely disposed handle 32. The side bars 30 are double-stepped so that a portion thereof can extend beneath the computing wheels and so that the portion bearing the transversely disposed 90 handle 32 will extend upwardly free and clear of the machine in a position where it can be readily grasped by the person operating the machine. These side bars 30 are also provided with downwardly extending 95 legs 33 so as to support the side bars in raised positions from the bottom of the casing 9.

It will be noted that the handle 32 travels close to the forwardly extending flat portion 100 of the casing, and that the numeral keys 1 lie on a slope of the casing, so that said keys are well protected from accidental injury by the enlarged part of the casing in which the computing wheels are journaled. Moreover 105 the handle 32 itself stands nearly at the height of the numeral keys and so helps to protect said keys.

The cross bar 31 is in the form of a plate which has its front edge a little behind the pins 3 to engage such of the pins 3 as may be projected downwardly by their associated keys 1, while its rear edge normally stands against lugs 32^a on the rack bars 5 to engage on the return stroke of the general operator 110 with said lugs 32^a to return these rack bars to their normal positions. When the handle 32 pulls the general operator forward, the cross bar 31 will come into engagement with said pins, moving the rack bars 5 forward, 115 amounts corresponding to the particular pins which are set thereon, so that the computing wheels 16 are turned to a corresponding extent by their racks 6. It will be seen that in this structure the racks 6 are located on the farther side of the computing wheel 16 from that portion which bears the pins 3 and from the position of the keys 1, that is to say, the computing wheel and the tens-carrying mechanism therefor are located in- 120 125 130 135

termidate the rack portion of the rack bars and the pin portion of the rack bars.

In order that the general operator may not be given a partial movement and then

5 returned, there is provided a lock which will force the general operator to be moved to the limit of its stroke in one direction before it can be returned in the opposite direction. This mechanism includes a stationary rack 16 34 with which may alternately engage locking dogs 35 and 36 pivoted on the general operator 29. A rocker 37 has pins 38 and 39 underlying respectively the dogs 35 and 36. When this rocker is swung to one position it 15 permits one of the dogs to drop to engage the rack, thus allowing the general operator to move only in one direction, and swung to another position it permits the other dog to engage the rack, thus allowing the general 20 operator to move only in the opposite direction. The rocker is shifted from one position to the other when the general operator reaches the limit of its movement in each direction, by cams 40 and 41 which are located 25 at the ends of the stationary rack 34. Each cam raises its end of the rocker 37 when it comes into engagement therewith. As will be seen by reference to Fig. 4, the rocker 37 is locked in either position by means of a 30 spring detent 42 which holds it till next shifted by a cam 40 or 41. The dogs 35 and 36 are faced in opposite directions so that one permits a movement in a direction which the other prevents, and the rocker is swung 35 so that one dog is shifted out at the same time that the other is shifted in; and this shifting occurs at the end of each stroke so that a complete movement in the opposite direction is the only movement of which the 40 general operator is capable.

For the purpose of returning all of the pins 3 to their normal positions after the rack bars 5 have been moved thereby to carry into the computing wheels the numbers 45 which have been set up, there is provided a pin-restoring plate 43 which is pivotally mounted on cranks 44 and 45, the latter being connected, so as to move the plate 43 always in a level position, by means of 50 links 46.

The general operator is provided with a cam hook 47 which, during the forward movement thereof, slips over a one-way spring pawl 48 provided on an arm 49 secured to one of the cranks 45. On the return motion, however, the hook 47 engages the pawl 48 on the opposite side so that it forms a rigid intermediary enabling the general operator to swing the pin-restoring plate 43 55 upwardly until it has forced all of the pins 3 to their normal upper positions, as shown in Fig. 3. The pin-restoring plate 43 can also be actuated directly, as when an error has been made, by an error key 50 which is 60 normally held in its uppermost position by

a spring 51 and has a stem extending downwardly in engagement with an arm 52 carried by the bell crank 44.

For the purpose of returning all of the computing wheels 16 to zero after they have been used to add up a sum, there is provided a zero key 53 which is normally held in a raised position by a spring 54, but is capable of being depressed so that its stem 55 will set a pin 56 provided on a special rack bar 57. This rack bar extends rearwardly where it is provided with a rack portion 58 arranged to mesh with a gear 59 (see Figs. 2 and 11) loosely mounted on the shaft 60 on which all the computing wheels 16 are journaled. The shaft 60 is held in its normal position by a spring dog 61 which engages a notch 62 provided in a disk 63 secured to the shaft 60. The gear 59 has a one-way clutch connection 170 comprising a cam socket and a spring-pressed ball so that when the general operator is actuated to shift the rack bar 57 by engaging with the pin 56, the shaft 60 will be given a complete rotation in one direction.

The shaft 60 is provided with a series of sockets 64 and 65 for spring-pressed one-way ball clutches which are adapted to be pressed out into cam sockets 66 in the hub 20 of all of the computing wheels. The clutches are so arranged that no matter what the previous position of the computing wheel, when a ball clutch comes into engagement with its socket 66, it will rotate its disk or computing wheel until it brings it to "0." The socket 65 for the units wheel is located one step in advance of the others so that it will bring the units computing wheel to zero, thereby starting a tens-carrying operation which on the return stroke of the operator will be carried to all the other computing wheels causing them to be turned to zero.

The drive for the assisting shaft 24 of the tens-carrying mechanism is obtained from the general operator during a return stroke thereof, by means of a gear 67 meshing with a rack 68 provided on one of the side bars 30. The gear 67 meshes with a gear 69 mounted on the shaft 24 and connected thereto by a one-way clutch 171 so that the shaft 24 will rotate solely on the return movement of the general operator and for one complete revolution only. The shaft 24 is held in its normal idle position, like the shaft 60, by a dog 71 engaging a notched disk 72.

The shock and noise incident to the pulling of the rack bars 5 backwardly is taken up by a felt buffer 73 located in front of the machine above the guiding blocks 13 and 14. When carrying the machine about from place to place a pivoted bail 74 may be used as a carrying handle. It will thus be seen that there is provided a simple, compact adding machine with a considerable capacity.

4
which is capable of being readily operated, and which can be carried from place to place without any great inconvenience so that a single machine can be used by a number of 5 different persons to verify books at different places.

Variations may be resorted to within the scope of the invention, and portions of the improvements may be used without others.

10 Having thus described my invention, I claim:

1. The combination with a series of computing wheels, rack bars arranged to rotate said wheels, legs projecting downwardly to 15 support said rack bars in a raised position, and guiding means engaging certain of said legs to confine the movement of each of said rack bars to a certain plane.

2. The combination with a series of computing wheels, rack bars arranged to rotate said wheels, a series of pins on each of said bars to determine the extent of movement thereof, means for setting said pins to project downwardly, means for holding said 25 bars in a raised position to permit the setting of said pins, and a series of guiding blocks spaced apart from each other and arranged on opposite sides of each of said bars to form guiding ways therefor.

30 3. The combination with a series of computing wheels, rack bars arranged to rotate said wheels, a series of pins on each of said bars to determine the extent of movement thereof, and a general operator comprising 35 a pair of side bars, a cross bar connecting said side bars and arranged to engage the set pins to move said rack bars, and a transversely disposed handle connecting said side bars.

40 4. The combination with a series of computing wheels, of rack bars arranged to rotate said computing wheels, keys for determining the extent of movement of said 45 rack bars, a general operator for shifting said rack bars, said general operator comprising a pair of side bars stepped so that a portion thereof will extend under said computing wheels and a portion thereof will extend above the machine, a handle transversely disposed and connecting said last 50 mentioned portion, and a cross bar arranged to operate said rack bars and connecting said first-mentioned portion.

55 5. The combination with a series of computing wheels, of rack bars arranged to rotate said computing wheels, keys for determining the extent of movement of said rack bars, and a general operator for moving said rack bars, said general operator 60 comprising a pair of side bars spaced apart from each other and connected by a cross bar in the form of a plate, the side bars each comprising a pair of L-shaped stepped portions extending at one end beneath said 65 computing wheels and at the other end out-

side of and in front of the body of the machine, a handle connecting said side bars located above and in front of the machine in a position convenient to the operator, and legs extending downwardly from said side 70 bars to hold them in a raised position.

6. The combination with a series of computing wheels, of a series of racks arranged to rotate said computing wheels, a general operator for manipulating said racks, tens-carrying mechanism for said computing wheels, said general operator comprising a pair of side bars projecting within and without the machine, a transversely disposed handle connecting said side bars, one 80 of said side bars having a rack formed thereon, and gearing driven by said rack for driving said tens-carrying mechanism.

7. The combination with a series of computing wheels, of rack bars arranged to rotate said computing wheels, a series of pins on each of said rack bars, means for setting said pins to determine the extent of movement of said rack bars, a pin-restoring plate mounted for movement on one side of said 90 rack bars, a plurality of cranks for pivotally supporting said plate, an arm connected to one of said cranks, a one-way pawl on said arm, a general operator for manipulating said rack bars, and a fixed hook on said 95 general operator adapted to engage said pawl to manipulate said pin-restoring plate.

8. The combination with a series of computing wheels, of rack bars arranged to rotate said wheels, pins on said rack bars, means for setting said pins, a general operator arranged to engage the said pins to manipulate said rack bars, said general operator comprising a pair of side bars, a cross plate connecting said bars and engaging 100 said pins, a transversely disposed handle connecting said side bars, and legs supporting said side bars in the raised position, a pin-restoring plate underlying all of said 105 pins, a plurality of cranks for movably supporting said plate, an arm on one of said cranks, a hook carried by said general operator to engage said arm when said general operator moves in one direction so as to shift said plate to restore said pins to their 110 normal positions, an arm on another of said cranks, and a key engaging said arm to operate said plate to restore said pins.

9. The combination with a casing, of a series of computing wheels in said casing, means for rotating said computing wheels, indexing devices, and a general operator extending partly within said casing beneath said computing wheels to a position convenient to coöperate with said indexing devices, and extending partly without said casing to a point convenient to the operative, and having a transverse exterior handle adjacent to the casing.

10. In a computing machine, the combina-

tion with numeral keys and computing wheels, of members on which numbers are temporarily set up, a casing in which said wheels and members are confined, a general operator for carrying numbers from said members into said wheels, a handle for said general operator lying adjacent the surface of said casing and traveling adjacent said surface, and an enlarged portion of said casing extending beyond said handle, said enlarged portion containing the computing wheels.

11. In a computing machine, the combination with a casing and keys projecting therefrom, of computing wheels in an enlarged portion of said casing, members on which numbers are temporarily set up by said keys, a general operator for carrying the numbers so set up into said wheels, and a handle for said general operator normally standing ad-

jacent said keys; said handle and said enlarged portion of the casing forming a protection for the keys.

12. In a computing machine, the combination with a casing, of numeral wheels located in an enlarged portion of said casing, members on which numbers are temporarily set up, keys in an extension of said casing of less size so that said casing is of least size where it faces the operative, a general operator for carrying the numbers set up by said keys into said computing wheels, and a handle for operating said general operator extending across said machine near said keys and between them and the operative.
